ADJUSTABLE CHAIR BACK

Harry J. Hemminger, Savannah, and Cecil W.
Hawks, Hayesville, Ohio

Application September 24, 1936, Serial No. 102,344

4 Claims. (Cl. 155—158)

The invention relates to chairs of the general type used by barbers, beauty operators, dentists and the like and more particularly to a chair of this general character having a vertically adjustable back.

When a child comes to a barber shop for a haircut or the like, it is customary for the barber to either place a box upon the seat of the barber chair or a board across the arms of the chair 10 for the child to sit on so as to raise his head above the top of the chair back in order that the barber may reach over the back of the chair to cut the hair upon the back of the child's head and neck.

15 It has also been found by experience that many adults of short stature, particularly women, when seated in a barber's chair are not tall enough for the barber to easily work upon the back of the head and neck, making it necessary for the barber to reach down over the chair back while 20 the customer must lean forward.

The object of the present improvement is to overcome such difficulties by providing a vertically adjustable chair back which may be quickly 25 and easily adjusted to any desired height so that the top of the chair back may be positioned just below the back of the occupant's neck, permitting the barber to have easy access to the back of the head and neck.

30 A further object is to provide such an adjustable chair back without in any way interfering with the usual construction or operation of chairs of this general type, permitting the chair back to be tilted backward to any desired angle.

35 The above objects together with others which will be apparent from the accompanying drawing and the following description, or which may be later referred to, may be attained by constructing the improved chair in the manner illustrated in the accompanying drawing, in which 40

Figure 1 is a side elevation of a chair provided with a vertically adjustable back in accordance with the invention; and

Fig. 2, a section taken as on the line 2—2, 45 Fig. 1.

Similar numerals refer to similar parts throughout the drawing.

The improved chair may include the usual cylindric pedestal 10 within which is mounted 50 the vertically adjustable ram 11 by means of which the entire chair as a unit may be raised or lowered as in usual practice.

The chair includes a metallic frame 12 mounted upon the ram 11 and provided with the usual 55 upholstered seat 13. As in usual practice, the

horizontal arm rests 14, back rest indicated generally at 15 and foot rest 16 are designed to be moved in unison so as to tilt the back 15 and simultaneously raise the foot rest 16.

This may be accomplished in usual manner by 5 providing the rigid arms 17 and 18 at the rear and front corners of the bottom frame 12, links 19 being pivotally connected to the arms 17 as at 20 to support the back, while the arms 21 carrying the foot rest are pivoted intermediate their 10 ends upon the rigid arms 18 as indicated at 22.

The chair arms 14 may be provided at their front and rear ends with the depending rigid ears 23 and 24 respectively, for pivotal connection to the upper ends of the arms 21 and links 15 19 as indicated at 25 and 26 respectively, all as in usual and well known practice. Thus as the chair back 15 is tilted backward upon the pivot 20, the chair arms 14 will move backward and slightly downward while the foot rest 16 will be 20 swung upward and forward.

In carrying out the invention, so as to provide for vertical adjustment of the chair back 15 relative to the chair seat, the links 19, instead of being rigidly connected to the chair back as in usual and well known practice, are provided with rearwardly disposed extensions carrying tubular guides 27 through which are slidably located the upright guide rods 28, the upper and lower ends of which may be bent inwardly as 25 at 29 and provided with attaching ears 30 connected to the metal frame 15 of the chair back as by rivets 31 or the like. This chair back frame 15 may be upholstered in usual manner as indicated at 32, providing a cushion for the 30 back of the occupant.

Thus it will be seen that the entire chair back may be vertically moved relative to the chair seat. Any suitable means may be provided for the purpose of holding the chair back in vertically adjusted position. The means shown in the drawing comprises a ratchet tooth rack 33 attached to the front of the back frame 15 at each side of the cushion 32, as by rivets 34 or the like.

A pawl may be mounted upon each link 19 for engagement with the ratchet teeth of the racks 33, these pawls being indicated at 35 and pivotally located through ears 36 forward upon the tubular guides 27, as indicated at 37.

In order to simultaneously operate both pawls, they may be formed as the extremities of a horizontally disposed bar 38 which extends across the back of the chair back, providing a handle by means of which the pawls may be tilted into 50 55

or out of engagement with the ratchet teeth.

It will be seen that the chair back may be quickly and easily adjusted to any desired height, one hand being placed beneath the frame 15 of

5 the back while the other hand grasps the bar

38. By raising this bar both pawls are moved out of engagement with the ratchet teeth and the back may be slidably moved up or down to the desired height and the pawls re-engaged with the

10 ratchet teeth to hold the back in the adjusted position.

It will be seen that sufficient vertical adjustment of the back is provided to position the same at the correct height to place the top of the back 15 below the head of the occupant regardless of whether a child or person of small height is seated in the chair, thus permitting the barber or other operator to have free access to the back of the head and neck of the occupant, over the 20 top of the chair back.

Although one particular form of mechanism is illustrated and described for vertically adjusting the chair back, it should be understood that the invention is not restricted to any such mechanical means but may be accomplished in many 25 different ways without departing from the spirit of the invention as set forth in the claims.

We claim:

1. A chair for use by barbers and the like including a seat frame, substantially upright links 30 pivotally connected at their lower ends to the front and rear portions of the seat frame at each side thereof, substantially horizontal arm rests pivotally connected to the upper ends of said links, rearwardly disposed extensions upon the rear links, normally upright tubular guides carried by said rearwardly disposed extensions, a normally upright back rest, guide rods fixed to the sides of the back rest and slidably mounted 35 in said tubular guides so as to slide said back rest up and down in a path behind the seat frame permitting the lower portion of the back rest to move to a point below said seat frame, and means for holding said back rest in adjusted position.

40 45 2. A chair for use by barbers and the like including a seat frame, substantially horizontal arm rests, means supporting the arm rests above the

seat frame, rearwardly disposed extensions connected to said means extending to a point rearward of said seat frame, normally upright tubular guides carried by said rearwardly disposed extensions, a normally upright back rest, guide rods fixed to the sides of back rest and slidably mounted in said tubular guides so as to slide said back rest up and down in a path behind the seat frame permitting the lower portion of the back rest to move to a point below said seat frame, and means for holding said back rest in adjusted position. 5 10

3. A chair for use by barbers and the like including a seat frame, substantially horizontal arm rests means supporting the arm rests above the seat frame, rearwardly disposed extensions connected to said means extending to a point rearward of said seat frame, a normally upright back rest substantially vertically slidably mounted upon said extensions so as to slide up and 15 down in a path behind the seat frame permitting the lower portion of the back rest to move to a point below said seat frame, forwardly disposed ratchet teeth at each side of the back rest, a horizontally disposed bar located behind the back 20 rest and having its ends bent forwardly and then inwardly and pivoted upon said rearwardly disposed extensions and arranged to engage said ratchet teeth. 25

4. A chair for use by barbers and the like including a seat frame, substantially upright links pivotally connected at their lower ends to the front and rear portions of the seat frame at each side thereof, substantially horizontal arm rests pivotally connected to the upper ends of said links, rearwardly disposed extensions upon the rear links, a back rest substantially vertically, slidably mounted upon said rearwardly disposed extensions, forwardly disposed ratchet teeth at each side of the back rest, a horizontally disposed 30 bar located behind the back rest and having its ends bent forwardly and then inwardly and pivoted upon said rearwardly disposed extensions and arranged to engage said ratchet teeth. 40
